UNITED STATES PATENT OFFICE

149,977

DESIGN FOR AN OVERSHOE BOOT

Alfred E. Shaffer, Mishawaka, Ind., assignor to Mishawaka Rubber and Woolen Manufacturing Company, Mishawaka, Ind., a corporation of Indiana

Application August 17, 1946, Serial No. 132,610

Term of patent 14 years

(Cl. D7—4)

To all whom it may concern:

Be it known that I, Alfred E. Shaffer, a citizen of the United States, residing at Mishawaka, in the county of St. Joseph and State of Indiana, have invented a new, original, and ornamental Design for an Overshoe Boot, of which the following is a specification, reference being had to the accompanying drawing, forming part thereof.

Fig. 1 is a perspective view of an overshoe boot embodying my design as it appears in its loose-fitting form;

Fig. 2 is a similar perspective view showing the same overshoe boot in its optional folded form;

Fig. 3 is a top view of the overshoe boot as it appears in Fig. 1; and

Fig. 4 is a top view of the overshoe boot as it appears in Fig. 2.

I claim:

The ornamental design for an overshoe boot, as shown and described.

ALFRED E. SHAFFER.
